UNITED STATES PATENT OFFICE.

OSCAR E. EKLUND, FREDERICK G. FOLBERTH, AND WILLIAM M. FOLBERTH, OF SAN FRANCISCO, CALIFORNIA.

INHALER.

1,035,954.

Specification of Letters Patent. Patented Aug. 20, 1912.

Application filed October 21, 1909. Serial No. 523,897.

To all whom it may concern:

Be it known that we, OSCAR E. EKLUND, FREDERICK G. FOLBERTH, and WILLIAM M. FOLBERTH, citizens of the United States, and residents of San Francisco, in the county of San Francisco, California, have invented certain new and useful Improvements in Inhalers, of which the following is a specification.

10 This invention relates to inhalers for administering anesthetics and its objects are to improve the construction whereby the admission of the anesthetic to the face piece may be closely regulated.

15 The invention generally stated consists in a vaporizing chamber connected to a face piece by passage or tube. This vaporizing chamber preferably forms a receptacle for receiving the liquid anesthetic. A valve simultaneously regulates the admission of air to the vaporizing chamber and the admission of the anesthetic and the air to the tube or passage. The vaporizing chamber is provided with a removable base which has 20 mounted thereon a number of wicks which provide a vaporizing surface of large area. The valve forms a removable cover for the vaporizing chamber and the whole apparatus is so constructed that it may be easily 25 taken apart and cleaned. The face piece and the vaporizing chamber are connected by a double joint whereby they may be relatively moved about intersecting axes. In this way the vaporizing chamber may be 30 maintained level whether the patient lies on his side or on his back. The face piece is provided with a hollow rubber ring which closely fits the face of the patient.

In the drawings, Figure 1 is an elevation 35 showing this invention; Fig. 2 is a top plan view; Fig. 3 is a section on the line 3—3, Fig. 2; Fig. 4 is a section on the line 4—4, Fig. 3; Fig. 5 is a partial elevation at right angles to Fig. 1.

40 Referring to the drawings, 10 designates a casing which forms a receptacle for receiving the anesthetic and the vaporizing chamber. The casing is provided with a pair of spaced bearing lugs 11, 12, the bearing lug 11 being in the form of a fork. The bearing lug 12 is provided with a recessed bearing 13 and the bearing lug 11 receives a sleeve 14, also provided with a recessed bearing 15. The T-shaped member 16 is mounted 45 in the recessed bearings 13 and 15 and is pro-

vided with an arm or stem 17 which engages a bearing in the face piece 18. The face piece has secured to it a hollow rubber ring 19 which is fastened to the face piece in any suitable manner.

60 A main pipe 20 extends from the L-shaped part 20' to the upper end of the vaporizing chamber and is connected thereto by a port 21. The vaporizing chamber is also provided with an air inlet port 22 which is located on the opposite side of the chamber from the port 21. A cover 23 is removably mounted on the vaporizing chamber and is provided with ports 24, 25, adapted to operate with the ports 21 and 22 respectively. These ports are cut in a downwardly extending flange 26 by means of which the cover 23 is rotatably mounted in the casing 10. The cover is also provided with an air inlet or port 27 which communicates with a 70 chamber 28 and the flange 26 has cut therein a port 29 located on the plane of the ports 21 and 24. A handle 30 is secured to the cover 23 and the cover is also provided with a circumferential slot 31 cooperating with a stop lug 32 upon the casing 10. The pipe 20 is secured to the L-shaped part, 20' and the casing 10 in any suitable manner, preferably by brazing. A circular base 33 is provided with a number of wires 34 which receive wicks 35, the wires forming supports for the wicks. The base 33 is loosely mounted in the bottom of the chamber and therefore may be removed for the purpose of 75 cleaning the same.

90 An inlet valve 36 is mounted on a pivot pin 37 in the bearing lug 12 and an exhaust valve 38 is similarly mounted upon a pivot pin 39 in the sleeve 14. Both valves are weighted so as to remain normally in closed 95 position, shown in Fig. 3. An absorbent wick 40 is mounted beneath the exhaust valve 38 for the purpose of absorbing the moisture which collects on the valve.

100 The vaporizing chamber 10 receives the fluid anesthetic which is absorbed by the wicks 35, the wicks providing a vaporizing surface of large area. By means of the cover or valve 23 the supply of anesthetic and air may be closely regulated. In the 105 position shown in the Figs. 3 and 4 the air inlet port 22 and the vapor port 21 are entirely open and the air inlet port 29 is entirely closed. Therefore in this position of the valve the percentage of anesthetic in the 110

air which is inhaled by the patient is a maximum. The air entering through the air inlet port 22 passing through the chamber and becoming laden with the vaporized anesthetic passes down the pipe 20 and is drawn in the patient's lungs through the valve 36, as the patient inhales. As the patient exhales the valve 36 is automatically closed and the exhaust valve 38 opens and allows the gases to be exhausted into the atmosphere. By means of this construction it is always insured that a fresh supply of air and anesthetic will be supplied to the patient. Since this supply can be kept constant, the condition of the patient may be closely regulated. More or less moisture will be collected on the exhaust valve 38 but this will be absorbed by the absorbent wick 40. By turning the handle 30 clockwise, as shown in Figs. 2 and 4, the port 22 will be closed, the port 21 will be closed to the vaporizing chamber and will be opened to the air passage 27 by means of the port 29. The ports 24, 25 and 29 are of the same area, therefore, the handle in its movements will close ports 24 and 25 the same amount as it will open port 29 and vice versa. The total amount of port openings to the pipe 20, and thus the volume of air or mixture supplied to the patient, will therefore be constant at all times.

The handle 30 may be thrown at any time to one extreme position to connect the pipe 20 with the atmosphere through the port 29 and the passage 27. In this position the port 21 and the port 22 will be entirely closed to the vaporizing chamber. The edge of the slot may be provided with a scale to indicate the amount of port opening and thus the percentage of anesthetic in the mixture.

The face piece is movable about a horizontal axis by swinging in the recessed bearings 13, and movable about a vertical axis by swinging about the stem 17. Therefore the vaporizing chamber may also be kept perfectly level and by swinging the face piece and the T shaped member 16 about the horizontal axis to different positions, the apparatus may be used whether a patient is lying on his side or on his back. The sleeve 14 is removable endwise, and by removing the sleeve the face piece and the T, 16 may be removed from the casing 10 by an endwise movement to the right, Fig. 3.

It is obvious that various changes may be made in the details of construction without departing from the spirit and scope of the

invention, and it is therefore to be understood that the invention is not to be limited to the specific construction shown and described.

Having described the invention what is claimed is,

1. In an inhaler, the combination with a face piece, of a vaporizing chamber connected to said face piece, a cover slidingly fitted on said vaporizing chamber, said cover having an air inlet and a channel formed therein, and means whereby said cover may be moved to place said channel in communication with said face piece.

2. In an inhaler, the combination with a face piece, of a vaporizing chamber connected to said face piece, a port connecting said face piece and chamber, a cover for said chamber, a flange on said cover engaging said chamber wall, ports in said flange cooperating with said first port, an air inlet in said cover, a channel formed in said cover connecting said air inlet with one of said flange ports, and means whereby said cover may be rotated to place said last flange port in communication with said first port.

3. In an inhaler, the combination with a face piece, a vaporizing chamber forming a receptacle for the inhaling fluid, and a tube connecting the face piece and vaporizing chamber, of a regulating slide valve forming a removable cover for the chamber.

4. In an inhaler, the combination with a face piece, a vaporizing chamber forming a receptacle for the inhaling fluid having an air inlet, and a tube having an air inlet and connecting the face piece and vaporizing chamber, of a slide valve arranged to regulate the supply of air and vapor to the tube, the said valve forming a removable cover for the chamber.

5. An inhaler having an exhaust passage, a valve in said passage, and absorbent material located beneath the valve.

In testimony whereof we affix our signatures in presence of two witnesses.
